INTERNESTABLE SERVICE BASKETS

Benjamin Gold, Brooklyn, N. Y., assignor to Handy Folding Pail Co., Inc., New York, N. Y., a corporation of New York

Application June 9, 1955, Serial No. 514,300

6 Claims. (Cl. 150—51)

This invention relates to improvements in internestable service baskets and more particularly to a strong and durable basket of relatively light weight having tapered enclosing walls permitting internested stacking thereof and provided with a flexible handle part which also serves as a supporting sling for a similar basket nested therein.

Internestable service baskets made in accordance with this invention are particularly designed for customers' use in carrying selected merchandise to the pay counter of self-service stores such as self-service food, drug, hardware and novelty stores, department stores and so-called ten cent stores. These improved service baskets are designed to provide a more convenient and less expensive medium for customer transportation of selected merchandise items and articles to the pay counter of self-service stores than is provided by the expensive and cumbersome rolling carts as presently used.

These improved service baskets are preferably assembled from a strong and sturdy cage framework formed from metal or plastic bands or wire of substantial stiffness. The cage framework comprises top and bottom hoops of generally rectangular outline, joined together by spaced vertical ribs or stays; the bottom hoop being somewhat smaller than the top hoop to permit tapered nesting of the finished baskets. The framework is covered by an enclosing hood which is telescoped thereover to provide the bottom and sides of the basket. The enclosing hood may be advantageously formed from strong and durable fabric such as canvas or duck which may be attractively and distinctively colored and decorated, and may be inexpensively manufactured from two pieces, one piece being shaped to form the bottom section and the second piece being sewn thereto to provide the enclosing side wall section. The top edge of the enclosing side wall section is infolded over the top frame and securely stitched to encase the top hoop in the tubular upper portion of the hood covering as thus formed.

The handle part is formed from strong and durable but flexible material such as cotton, duck, or other textile, leather or other fibrous composition, suitably decorated to harmonize with the hood covering of the basket body. The handle part may be economically manufactured from three strips, two strips providing a pair of inverted V-shaped yoke sections whose terminal ends are secured to the top hoop of the basket body, and the third strip providing a bridging section which is stitched to the apex portions of the yoke sections. The handle part has an overall length which will provide a convenient carrying handle when the bridging section thereof is in the hand, but possesses sufficient flexibility so that it will drop of its own weight into the basket when released, and is so proportioned with respect to the depth and taper of the basket body that approximately two-thirds to three-fourths of the height of a similar basket may be nested within and freely supported by the sagging handle part of the basket therebelow. As thus constructed, the nested basket is free of gripping contact with the basket in which it is nested and freely saddlestherein. A

2

customer, entering the self-service store, may thus pick up the fully accessible and sagging handle part associated with the topmost basket and lift the topmost basket from the basket stack without disturbing the stacked relation of the basket or baskets therebelow.

Service baskets constructed in accordance with this invention, made to provide substantial carrying capacity, are nevertheless light in weight, strong and durable, and can be manufactured at relatively low cost to provide an inexpensive, highly convenient, and space-saving transportation medium for the accommodation of customers of self-service stores. Service baskets constructed in accordance with this invention also find useful application in the home delivery of all kinds of merchandise, and as a general utility basket for use in homes, various stores, and manufacturing and service establishments.

Other objects and advantages of this invention will become apparent as the disclosure proceeds.

Although the characteristic features of this invention will be particularly pointed out in the claims, the invention itself, and the manner in which it may be carried out, may be better understood by referring to the following description taken in connection with the accompanying drawings forming a part hereof, in which—

Fig. 1 is a perspective view illustrating a typical form of service basket constructed in accordance with this invention with the handle part thereof shown in raised carrying position;

Fig. 2 is a perspective view of the cage framework for the basket;

Fig. 3 is a transverse cross-sectional view of the basket body as it would appear during assembly thereof and wherein the cage framework is in process of being telescoped into the flexible hood covering;

Fig. 4 is another transverse cross section showing the basket body as fully assembled and as it would appear after the cage framework has been fully telescoped into the flexible hood and the upper rim portion of the hood infolded and stitched to enclose the top hoop of the framework, this view also showing in phantom lines the upper rim-forming portion of the hood prior to infolding thereof;

Fig. 5 is a plan view of the assembled handle part as it would appear prior to attachment to the upper rim of the basket body;

Fig. 6 is a longitudinal section of the handle part as it would appear when viewed along line 6—6 of Fig. 5, this view illustrating further details of the handle part construction;

Fig. 7 is a fragmentary side elevational view of the basket body and handle part illustrating the manner in which the legs of the handle yoke straps may be attached and secured to the top rim of the basket body;

Fig. 8 is an enlarged fragmentary cross-sectional detail taken along line 8—8 of Fig. 7 and further illustrating the manner in which the legs of the yoke straps are secured to the top rim of the basket body;

Fig. 9 is a perspective view of a plurality of completed baskets constructed in accordance with this invention and illustrating the manner in which the baskets may be freely internested in limited space and supported by the underslung handle part of the basket positioned therebelow; and

Fig. 10 is a transverse cross section of the basket stack as it would appear when viewed along line 10—10 of Fig. 9, this view further illustrating the manner in which the handle part serves as a supporting sling for the super-imposed basket as nested in the basket therebelow.

Similar reference characters refer to similar parts throughout the several views of the drawings and specification.

3

As shown in the drawings, the improved service basket of this invention comprises a skeleton frame or cage 1 enclosed within a flexible hood 5 which together provide the basket body, and a flexible handle part 10 which is joined to the upper rim of the basket body. The skeleton frame as shown in Fig. 2 comprises a top hoop 2 and a bottom hoop 3, both preferably of substantially rectangular outline, with the bottom hoop 3 of slightly smaller size than the top hoop 2 to provide the required taper for the basket body. The top hoop 2 and bottom hoop 3 may be made of relatively heavy and stiff metal or plastic wire or bands of any desired cross-sectional shape whose ends are suitably welded or permanently joined as at 2' and 3' to provide continuous top and bottom hoops 2 and 3. The top and bottom hoops are joined by a series of spaced connecting ribs or stays 4 whose ends are welded or permanently bonded as at 4' to the hoops 2 and 3. The skeleton frame as thus constructed provides a strong and sturdy cage framework which maintains the shape of the basket body.

The enclosure hood 5 is preferably formed of strong, durable and flexible sheet material such as plastic sheeting or a durable textile such as canvas or duck cloth. The sheet material may be suitably colored, decorated or imprinted to best suit the purpose for which the basket is to be used. The enclosure hood 5 comprises a bottom forming section 6 of flexible sheet material which is contoured in conformity with the bottom hoop 3 of the skeleton frame. The enclosing body wall section 7 of the hood is formed from two elongated strips of selected flexible sheet material of sufficient length to extend end to end around the body of the skeleton frame. The lower edge of the body wall section 7 presents an edging portion 7' which is secured as by stitching 7" to embrace the peripheral edge of the bottom forming section 6 as shown in Figs. 1, 3 and 4. The free end edges of the side wall forming strips are secured together along vertical seams 8 in a manner to provide a tapered body section which may be snugly telescoped over the skeleton frame 1 in snug fitting relation thereto as shown in Figs. 3 and 4.

After the enclosing hood 5 has been telescoped over the reinforcing cage 1, as shown in Fig. 4, the upper edge portion 9 of the body wall section 7 of the hood is folded inwardly to overlie and embrace the top hoop 2 of the cage and is stitched as by stitching 9' to provide a tubular portion which completely encloses the top hoop 2. As thus constructed, the enclosure hood 5 provides an outer facing for the reinforcing frame 1 and is suspended from the top hoop 2 thereof, but need not be otherwise secured to the reinforcing frame.

The flexible suspension handle 10 is formed by a pair of yoke straps 11 formed of strong and durable but flexible sheet material such as a strong textile, plastic or leather. Where a textile is used, the yoke straps 11 may be of double-ply. Each yoke strap 11 presents an overfolded portion medially thereof to provide the apex saddle 12 of an inverted V-shaped yoke strap having outwardly flaring legs 13. The end of each flaring leg 13 presents an upfolded portion 14 extending over the outside face of the top rim of the basket body as shown in Figs. 7 and 8, and a downfolded portion 15 which overlies the inside face of the top rim of the basket body. Either stitching or one or more rivets 16 may be used to secure the end of each yoke leg 13 to the top frame of the basket.

A bridging strap 17 made of flexible leather, plastic or cloth of either single or plural-ply thickness presents end portions 18 which embrace the apex saddles 12 of the yoke straps 11 and are securely sewn as by stitching 18' thereto. The bridging strap 17 provides a comfortable hand grip by means of which the basket is carried.

The overall length of the flexible sling handle 10 is so dimensioned that it will freely sag when unsupported into the basket body, with the yoke straps 11 extending

5 into the basket for a distance of approximately three-fourths of its depth and with the bridging strap 17 extending transversely across the basket width as shown in Figs. 9 and 10, with the yoke straps 11 directly adjacent the inside face of the hood side walls. The handle part 10 then provides a sling on which the bottom panel 6 of a nested basket will rest to provide a complete sling support therefor as shown in Figs. 9 and 10. The side walls of the basket body are so tapered as to permit nesting of one basket into a similar basket for approximately three-fourths of the basket depth without friction gripping contact between adjacent baskets. As thus constructed, the customer will find the inwardly sagging handle of the topmost basket as shown in Figs. 9 and 10 conveniently accessible, and by exerting an upward lifting force on the sagging handle, the topmost basket to which it is attached may be readily lifted from the stacked baskets without disturbing the stacked relation of the basket or baskets therebelow.

20 Service baskets constructed in accordance with this invention are particularly suited and adapted for use by the customers in self-service stores, but finds many additional uses where a strong and durable but light-weight basket of commodious capacity is desired. The enclosure hood portion of the basket may be made of various flexible sheet materials such as strong and durable plastic sheets, textiles and various fibrous compositions, suitably colored, imprinted or decorated to satisfy individual requirements.

25 While certain novel features of this invention have been disclosed herein and are pointed out in the claims, it will be understood that various omissions, substitutions and changes may be made by those skilled in the art without departing from the spirit of this invention.

30 What is claimed is:

1. A service basket having a basket body presenting a bottom wall, tapered side enclosing walls, and a handle part formed from flexible material which includes, a pair of V-shaped yoke sections each presenting an apex portion and flared legs extending therefrom, means for securing the ends of said legs to the upper portion of the basket body, and a bridging section extending between and secured to the apex portions of said paired yoke sections and providing a hand grip when said handle part is lifted to basket carrying position, said handle part when unsupported being sufficiently flexible to sag into the upright basket body with the yoke sections thereof extending inwardly of the upright basket body for a distance of more than one half but less than four-fifths of the height of the basket body and with said bridging section extending transversely within the basket body, said sagging handle part being designed to provide a supporting sling for a nested basket body of similar shape and contour with the body and side walls of the nested basket substantially free of friction gripping contact with the walls of the basket whose handle part provides the sole support for the nested basket.

2. A service basket having a basket body presenting a bottom wall, tapered side enclosing walls, a reinforced top rim, and a handle part formed from flexible material which includes, a pair of V-shaped yoke sections each presenting an apex portion and flared legs extending therefrom, means for securing the ends of said legs to the top rim of the basket body, and a bridging section extending between and secured to the apex portions of said paired yoke sections and providing a hand grip when said handle part is lifted to basket carrying position, said handle part when unsupported being sufficiently flexible to sag into the upright basket body with the yoke sections thereof extending inwardly of the upright basket body for a distance of approximately one-half to three-fourths of the height thereof and with said bridging section extending transversely within the basket body, said sagging handle part being designed to provide a sling which serves as the sole support for a nested

basket body of similar shape and contour with the body and side walls of the nested basket substantially free of friction gripping contact with the walls of the basket whose handle part provides the sole support for the nested basket.

3. A plurality of internestable service baskets each having a basket body presenting a similar bottom wall, tapered side enclosing walls, a reinforced top rim, and a handle part formed from flexible material which includes, a pair of V-shaped yoke sections each presenting an apex portion and flared legs extending therefrom, means for securing the ends of said legs to the top rim of the basket body, and a bridging section extending between and secured to the apex portions of said paired yoke sections and providing a hand grip when said handle part is lifted to basket carrying position, each of said handle parts being sufficiently flexible to sag into its basket body when unsupported, with the paired yoke sections thereof extending inwardly of its basket body for a distance of more than one half but less than four-fifths of the height thereof and with said bridging section extending transversely within its basket body, each of said handle parts being designed to provide a sling support for the basket body nested therein with the body and side walls of the nested basket substantially free of friction gripping contact with the walls of the basket whose handle part provides the sole support for the nested basket.

4. A nestable service basket having a basket body which includes a tapered reinforcing framework presenting relatively stiff and rigid top and bottom hoops joined by a series of rigid vertically extending spacing ribs, a hood formed from flexible sheet material snugly telescoped over said reinforcing framework and presenting a bottom wall section shaped in substantial conformity with said bottom hoop and an enclosing side wall section embracing said vertical ribs, said side wall section having a tubular top portion embracing said top hoop and whereby said top hoop provides a reinforcing rim for the basket body and suspension support for said hood, and a handle part formed from flexible material which includes, a pair of V-shaped yoke sections each presenting an apex portion and flared legs extending therefrom, means for securing the ends of said legs to the top reinforcing rim of the basket body, and a bridging section extending between and secured to the apex portions of said paired yoke sections and providing a hand grip when said handle part is lifted to basket carrying position, said handle part when unsupported being sufficiently flexible to sag into the upright basket body with the yoke sections thereof extending inwardly of the upright basket body for a distance of more than one half of the height of the basket body and with said bridging section extending transversely within the basket body, said sagging handle part being designed to provide a sling support for a nested basket body of similar shape and contour with the body and side walls of the nested basket substantially free of friction gripping contact with the walls of the basket whose handle part provides the sole support for the nested basket.

5. A nestable service basket having a basket body which includes a tapered reinforcing framework presenting relatively stiff and rigid top and bottom hoops joined by a series of rigid vertically extending spacing ribs, said top and bottom hoops being substantially rectangular in outline with the bottom hoop of smaller dimension than the top hoop, a hood formed from flexible sheet material snugly telescoped over said reinforcing framework and presenting a bottom wall section shaped in substantial

conformity with said bottom hoop and an enclosing side wall section embracing said vertical ribs, said side wall section having a tubular top portion embracing said top hoop and whereby said top hoop provides a reinforcing rim for the basket body and suspension support for said hood, and a handle part formed from flexible material which includes, a pair of V-shaped yoke sections each presenting an apex portion and flared legs extending therefrom, means for securing the ends of said legs to the top reinforcing rim of the basket body, and a bridging section extending between and secured to the apex portions of said paired yoke sections and providing a hand grip when said handle part is lifted to basket carrying position, said handle part when unsupported being sufficiently flexible to sag into the upright basket body with the yoke sections thereof extending inwardly of the upright basket body for a distance of more than one half of the height of the basket body and with said bridging section extending transversely within the basket body, said sagging handle part being designed to provide a sling support for a nested basket body of similar shape and contour with the body and side walls of the nested basket substantially free of friction gripping contact with the walls of the basket whose handle part provides the sole support for the nested basket.

6. A nestable service basket having a basket body which includes a tapered reinforcing framework presenting relatively stiff and rigid top and bottom hoops rigidly connected by a series of rigid vertically extending spacing ribs, said top and bottom hoops being substantially rectangular in outline with the bottom hoop of smaller dimension than the top hoop, a hood formed from flexible sheet material snugly telescoped over the exterior of said reinforcing framework and presenting a bottom wall section shaped in substantial conformity with said bottom hoop and an enclosing side wall section embracing said vertical ribs and secured to the peripheral edge of said bottom wall section, said side wall section having a tubular top portion embracing said top hoop whereby said top hoop provides a top reinforcing rim for the basket body and suspension support for said hood and whereby said bottom hoop and spaced vertical ribs provide a shape-maintaining structure for the bottom wall section and side wall section of said hood, a handle part formed from flexible material secured to the top reinforcing rim of the basket body, said handle part when unsupported being sufficiently flexible to sag into the upright basket body and provide a supporting bridge extending transversely within the basket body and thereby provide a sling support for a nested basket body of similar shape and contour with the body and side walls of the nested basket extending into the receiving basket to a depth of more than one-half but less than four-fifths of the height of the receiving basket and with the nested basket as thus supported being substantially free of friction gripping contact with the walls of the receiving basket whose handle part provides the sole support for the nested basket.
